UNITED STATES PATENT OFFICE.

WASHINGTON M. POTTER, OF FREEDOM, PENNSYLVANIA.

SUSPENDERS.

Application filed November 16, 1921. Serial No. 515,580.

To all whom it may concern:

Be it known that I, WASHINGTON M. POTTER, a citizen of the United States, residing at Freedom, in the county of Beaver 5 and State of Pennsylvania, have invented certain new and useful Improvements in Suspenders, of which the following is a specification, reference being had to the accompanying drawings.

10 The present invention has for its purpose to provide a device of this kind wherein the elastic straps connect at the front and back, so that the shoulder engaging portions of the strap will fit closely along the base of 15 the neck in accordance with the weight suspended. The elastic straps which pass over the shoulders assume angles in the front and at the back.

Another purpose is the provision of a pair 20 of suspenders, by which the weight of the clothing suspended therefrom, does not interfere with the movement of the shoulders in any direction.

Still another purpose is the provision of 25 a pair of suspenders, which is simple, efficient and practical in construction, and may be cheaply manufactured and sold at a fair profit.

While the design and construction at present illustrated and set forth are deemed 30 preferable, it is obvious that as a result of a reduction of the invention to a more practical form for commercial purposes, the invention may be susceptible of changes, and 35 the right to these changes is claimed, provided they are comprehended within the scope of what is claimed.

The invention comprises further features and combination of parts, as will be herein- 40 after set forth, shown in the drawings and claimed.

In the drawings:—

Figure 1 is a view in perspective of the improved suspenders constructed in accordance with the invention, showing the position of the straps when engaged with the shoulders of the wearer;

Figure 2 is a plan view of the suspenders removed from the wearer;

Figure 3 is a sectional view on line 3—3 of Figure 2;

Figure 4 is a sectional view on line 4—4 of Figure 2; and

Figure 5 is a detail view showing how the 55 extension strap 7 is connected to the straps 2 and 3, illustrating the cover piece removed.

Referring to the drawings, 1 designates a pair of suspenders as a whole, which comprises a pair of elastic straps 2 and 3, constructed of any suitable material, such as 60 used for suspenders. The opposite ends of the straps 2 and 3 are spliced together as shown at 4 and 5. These splices are formed by first cutting the straps on angles, and the several edges are stitched together as at 6. 65

Stitched at 9 to the spliced ends of both ends of the pair of suspenders are the extension straps 7 and 8. The extension 7 is constructed of elastic material, and its end is folded, and has an adjustable buckle connection 10 with its body portion. A suitable metal suspender button engaging loop 11 is engaged in the fold of the extension 7, and is designed to engage with a button on the trousers, particularly in the front. It is the 70 purpose of the suspenders to wear them under the top or outer shirt, and in order to connect the button engaging loop with the button, the material of the shirt is fitted over the button and the button forced 75 through the loop. In this way the suspenders are hidden.

Where the extension strap 7 is attached to the splices of the straps 2 and 3, shields or fabric cover pieces 12 are stitched as at 13 to 80 the straps 2 and 3 and to the extension strap 7. These cover shields or pieces are on opposite sides of the suspenders. In fact the cover pieces are designed to be constructed 85 of pliable leather, such as used in the construction of suspenders.

The extension strap 8 is folded as at 14, and one end beyond the fold has a buckle 15 connected with the body portion of the 90 strap, so that the fold may be lengthened or shortened, in order to shorten or lengthen the suspenders. Where the extension strap 8 is attached to the straps 2 and 3, cover shields or pieces 16 are stitched at 17 upon the inner and outer faces of the 95 straps. These cover pieces or shields 16 may be constructed of any suitable pliable leather such as used in the construction of 100 suspenders.

A metal loop 18 engages the loop 14, and 105 connected to the metal loop 18 is the loop end 19 of a folded strap of leather or other pliable material 20. The opposite end portions of the folded strap of leather are stitched at 21 to the spliced ends of the 110 downwardly diverging elastic straps 22. The downwardly diverging elastic straps 22 have

their lower ends spaced a considerable distance apart, in order to provide suitable means for holding the trousers at the rear. Suitable metallic loops are carried by the 5 lower ends of the diverging elastic straps 22, and are designed to receive the suspender buttons 23 at the rear of the trousers.

The suspenders are worn under the outer or top shirt, the single metallic loop in 10 front being engaged with the outer shirt and the suspender button centrally in front, thus preventing the garments from sagging down, holding them uniformly in a certain position on the body, so that the clothing at no time 15 requires adjustment. The lower ends of the diverging elastic straps 22 are arranged farther apart than those of the ordinary suspenders, and relieves the pulling up action 20 of the trousers when the wearer is stooping, and also relieves the tension of the trousers at the crotch.

Owing to this particular construction of 25 suspenders with the lower ends of the diverging straps 22 spaced a considerably distance apart, the distance between the points 30 of the adjustment of the straps 22 to the trousers is somewhat greater than the spacing 35 of the corresponding straps of the ordinary trousers, so that together with the particular construction of the suspenders, a much greater part of the strain and pulling 40 is relieved from the wearer's shoulders when the wearer is in stooping posture. By providing a pair of suspenders to be worn under 45 the outer or top shirt, it permits the wearer to adjust the amount of fullness of the shirt over the shoulders, and also due to the shirt being attached to the trousers by the metallic loop fasteners, the shirt is prevented from working up out of the trousers. Owing 50 to the straps 2 and 3 engaging on the shoulders and extending toward each other at the front and rear, they will fit closely along the base of the sides of the neck, and 55 this tendency is greatly increased by the weight of the trousers, and for this reason the straps over the shoulder hardly ever need adjustment, the fact is that the straps tend

to work up toward the neck instead of down over the arm. 50

The invention having been set forth, what is claimed is:

1. A pair of suspenders comprising a pair of elastic straps adapted to engage over the shoulders of a wearer, said straps converging toward and connected together at their opposite forward and rear ends, means connected to the forward ends for operatively connecting the straps to the front of the trousers, shields overlying and secured to the rear ends of the straps, a strap secured between the shields and being folded adjacent its unattached end, a buckle attached to the terminal of the strap beyond the fold and operatively and adjustably receiving the body of the strap between the fold and where the end of the strap is secured between the shields, and a pair of diverging elastic straps connected together at their converging ends, means connecting the converging ends of the last mentioned straps to the fold, and means attached to the diverging ends of the last mentioned straps for attaching them to the rear of a pair of trousers. 60 65 70

2. A pair of suspenders, comprising elastic straps adapted to engage over the shoulders of a wearer, and converging together and connected at their forward and rear ends, means operatively connected to the converged connected rear ends of the straps for connecting them to the rear of a pair of trousers, a pair of shields secured to the converged connected forward ends of the straps, a strap secured between said shields and being folded, means connected to the fold of the last mentioned strap for operatively connecting the same to the front of the trousers, a double metallic loop connected to the terminal of the last mentioned strap beyond said fold and operatively receiving the body of said last mentioned strap for adjustably tightening the suspenders in front. 80 85 90

In testimony whereof I hereunto affix my signature.

WASHINGTON M. POTTER.
